VERNET H. KELLER, OF HATFIELD, MASSACHUSETTS.

TERMINAL CLIP.

1,025,573.

Specification of Letters Patent.

Patented May 7, 1912.

Application filed October 3, 1911. Serial No. 652,582.

To all whom it may concern:

Be it known that I, VERNET H. KELLER, a citizen of the United States of America, residing at Hatfield, in the county of Hampshire and State of Massachusetts, have invented a new and useful Terminal Clip, of which the following is a specification.

My invention relates to improvements in connecting devices on clips for the terminals of electric conductors, and more particularly to devices which are used to connect electric conductors with spark-plugs in internal-combustion engines of the ordinary types, although the application of said invention is not thus limited but is quite general in its scope; and said invention resides in certain parts and combinations of parts, including pivotally-mounted and spring-pressed jaws and means to produce or form a spark-gap, all as hereinafter set forth.

The objects of my invention are, first, to produce a simple, durable and comparatively inexpensive connector for attaching an electric conductor to and detaching it from the central electrode of a spark-plug or to the binding-post or other terminal of a telegraph, telephone, or other electrical instrument or apparatus, such conductor being securely and practically permanently fastened to said connector; second, to provide such a device with normally closed or self-closing jaws, to the end that the connection can be easily, quickly and conveniently made, and as readily and with equal facility broken, the jaws acting automatically in both cases and affording a good and sufficient electrical contact when in engagement with a terminal, and, third, to provide such a device with means to determine without difficulty whether or not the electrical circuit of which the clip forms a part is active, or, in other words, to ascertain whether or not the electric current is passing through said clip. This last is very important, because it frequently occurs that one (or more) of a series of spark-plugs, for example, fails to spark properly, it being then necessary to remove the spark-plugs one after another until the defective plug (or plugs) is discovered, unless provision is made for detecting the location of the difficulty by an examination of the connecting clips.

Other objects will appear in the course of the following description.

I attain the objects and secure the advantages of my invention by the means illus-

trated in the accompanying drawings, in which—

Figure 1 is a side elevation of a clip which embodies a practical form of my invention, the same having an electric conductor secured thereto and being itself attached to a spark-plug; Fig. 2, a top plan of said clip, the sleeve being in this view removed from the body portion of the clip to expose the spark-gap; Fig. 3, an enlarged longitudinal central section through said clip, all parts being in normal position, and Fig. 4, a top plan of a modified form of clip, the body of the same being in partial section.

Similar figures refer to similar parts throughout the several views.

In each of the views a short piece of an electric conductor appears at 1 and its insulation at 2.

As already noted, my connector or clip, although it may be used with electrical apparatus in general, is especially designed for use with spark-plugs of internal-combustion engines, for the purpose, therefore, of illustrating the practical application of said clip I show the same, in the first view, applied to a spark-plug, the connection being made directly with a clamping-nut 3 on the central electrode of said spark-plug. Such connection might be made at some other point on the clamping-nut, besides that shown, or with the central electrode direct. The spark-plug represented in connection herewith is of ordinary construction and needs no explanation, more especially in view of the fact that it forms no part of the present invention.

Passing now to the clip itself, it will be observed that the same comprises a hollow metallic body 4, which has a central slot 5 therein opening through one end and opposite sides thereof, such slot being in what might be termed the head of such body, and, furthermore, is externally and internally screw-threaded; a pair of metallic gripping or clamping members or jaws 6 at the slotted or head end of said body, which jaws are adapted to engage or release a spark-plug terminal member such as the clamping-nut 3, or a binding-post or equivalent terminal member of some other electrical device; an externally screw-threaded insulating plug 7, which has one end screwed into said body; a metallic cap 8 internally screw-threaded to fit the opposite end of said insulating plug onto which such cap is screwed and between

which and the adjacent end of said cap the inner end of the conductor 1 is secured, after passing through a central opening in said cap end, in the usual manner and as represented in 9, in Fig. 3; and an internally screw-threaded sleeve 10, of insulating material, adapted to be screwed onto said body and to cover all of the parts between the front end portion or head of said body and 10 the adjacent end of the insulator 2.

The body 4 and the cap 8 are retained at some distance apart by the plug 7, a gap being thus produced between the adjacent ends of said body and cap. Thus separated by 15 the insulating plug, the body and the cap are out of both physical and electrical contact, but, by nearly closing the gap just mentioned, between the adjacent ends of said body and cap, so that the spark can jump 20 across the intervening space, provision is made for the passage of the current, and also for ascertaining whether the circuit is active or inactive. Preferably such spark-gap is formed at a single point by means of 25 a projection from one adjacent edge or the other or projections from both of such edges, such a projection in any event extending toward the opposite or juxtaposed member but not actually coming into contact with 30 it. In the present case a projection or point 11 extends from the edge at the open end of the cap 8 toward the adjacent end of the body 4 and close enough to the latter to enable the current to jump across the intervening 35 space, sparks being produced in such space so long as the current remains active and thus giving visual evidence of such activity.

The jaws 6, which may be separately pivoted to the body 4, as at 12-12 in Figs. 2 and 3, or attached to the body by means of a single pivot 12, as shown in Fig. 4, are notched, indented or recessed just behind their outer or free ends, as represented at 13, 45 to enable said jaws when closed not only to grasp firmly an object between them, such as the clamping-nut 3, but also to insure a good electrical contact, and the aforesaid free ends are rounded in a manner to facilitate engagement with and disengagement from the clamping-nut or other terminal. The inner end portion of the jaws 6 in each case are received in the slot 5, wherein they are pivoted, and such portions operate in 50 such slot.

There being only one pivot 12, in the Fig. 4 construction, it is necessary for the inner end portions of the jaws 6 to lap by each other, while in the other construction such 60 end portions lie in the same plane. The jaws 6 which are arranged in the same plane with each other and are mounted on the two pivots are provided with beveled or divergent edges 14-14, each of which edges leads 65 from the inner end of the dividing line be-

tween the two jaws rearwardly or inwardly and laterally or toward the sides of the body 4 through which the slot 5 opens. Herein is found another difference between the two jaw constructions, since the divergent edges 14 are absent from the second construction 70 which appears in Fig. 4.

It will be seen that pressure exerted on the beveled edges 14 has a tendency to swing the jaws 6 on their pivots 12 in such a way as to close said jaws, that is, to actuate the outer and major portions of said jaws toward each other until their adjacent edges come into contact or their recessed parts 13 engage a terminal. The recessed parts 13 must be shallow enough to accommodate the jaws to the smallest terminal, so that they can tightly engage the same before the adjacent edges of the jaws come into engagement and so check further closing movement. 85

To produce the proper pressure on the beveled or divergent edges 14 and as a result of such pressure to maintain the jaws 6 normally in their closed condition, I have recourse to the construction and parts next described. The central bore in the body 4 is continued through into the slot 5 in said body and a spiral spring 15 is inserted in this bore between the end of the plug 7 that is in said body and the edges 14 or a follower in the form of a disk 16 that bears directly against said edges and receives the thrust from said spring. The spring 15 tends constantly to force the disk 16 against the edges 14 and to retain the jaws 6 in their closed condition, to the end that the resiliency of said spring must be overcome in order to separate said jaws at their outer ends or open them, the heels of the jaws then approaching each other and thrusting said disk rearwardly. The spring 15 is thus compressed between the plug 7 and the disk 16 to a greater extent than before, but acts to swing those parts of the jaws that are in advance of the pivots 12 toward each other again as soon as the superior force ceases to be an active factor. The plug 7 extends only 90 part way into the bore 17, so that there is 95 left ample room for the spring and follower 100 110 or disk.

The disk 16 is of a size which permits it to bear against the beveled edges 14 at a point which will produce the desired closing movement and keep the jaws normally in 115 their closed position, or, in other words, which enables said disk to bear against the heels of said jaws, such heels consisting of those portions of the jaws that are behind the pivots 12 and being designated by the 120 numeral 20—see Fig. 3. If the disk were so small as to bear against the edges 14 at 125 points where said disk could pass between the pivots in the absence of the jaws, the object of the disk and spring would be de- 130

feated because in that case the tendency of the spring would be to open the jaws. Under the present arrangement and normally the jaws are closed and kept closed with a sufficient amount of force, and the closing action is quick and strong.

In place of the spring 15 and the follower or disk 16, a looped spring 18 may be employed, as shown in the last view. Here the slot 5 does not communicate with the screw-threaded bore in the body 4 into which the plug 7 is inserted, and the inner edges of the lapped portions of the jaws 6 are curved or rounded off so as to allow said jaws to open without striking the inner end of said slot. The spring 18 has a central loop and extends forwardly and outwardly from such loop to notches 19-19 in the lateral edges of the jaws 6, where the ends of said spring are attached to said jaws, such ends being bent over and inserted in said notches. The effect of the action of the spring 18 on the jaws is practically the same as that of the spring 15. This construction may be somewhat cheaper than the other, but otherwise may not be so efficient and desirable. The pivots 12 in both cases are inserted in the bodies 4 and extend across the slots 5 in such bodies and through the inner end portions of the jaws 6 which are in such slots. The sleeve 10 may be screw-threaded throughout its entire length so that either end of the same can be screwed onto the body 4. The interior diameter of the sleeve 10 is large enough to permit said sleeve to be moved on the insulation 2 and the cap 8. The parts are assembled by first placing the sleeve 10 on the insulation 2, then inserting the denuded end of the conductor 1 which protrudes from said insulation in the cap 8 and screwing the plug 7 into said cap against the inserted part of said conductor, and finally screwing the body 4 onto said plug, the disk 16 and the spring 15 being placed in the bore 17 before screwing said body onto said plug, in the clip shown in the first three views. After thus assembling the parts, the sleeve 10 is moved into engagement with the body 4 and screwed thereon for the purpose of covering the jointed members and providing a suitable and convenient handle with which you hold the clip while connecting and disconnecting it. Either form of clip is attached to a terminal by simply presenting the in-turned front ends of the jaws 6 to the terminal and forcing said jaws onto said terminal with the latter in the recesses or recessed portions 13 of said jaws, the spring 15 or 18, as the case may be, yielding to permit such ends to pass the terminal, and then acting to close the jaws on the terminal and serving to retain them in firm contact therewith. The withdrawal of either clip is effected by grasping the sleeve 10

and pulling with sufficient force to overcome the resiliency of the holding spring by the separation of the jaws as their front ends slip past and off of the terminal. By unscrewing the sleeve 10 and sliding it back on the insulation 2 until the point 10 is exposed, the presence or absence of the current can be ascertained by observing whether or not sparks are being given off at the spark-grip, as hereinbefore noted.

I am aware that various changes and modifications in the shape, size, and construction of some or all of the parts of my device, besides those herein shown and described, such as will occur to one skilled in the art to which said device belongs, may be made without departing from the nature of my invention, wherefore I desire to include all such changes and modifications and to cover them by my claims.

What I claim as my invention, and desire to secure by Letters Patent, is—

1. A terminal clip comprising a body provided with pivotally-attached spring-pressed terminal-gripping jaws at its outer end, means for connecting an electric conductor with the inner end of said body, such means consisting in part of a cap, and a sleeve attached to said body to cover the jointed members and serve as a handle, such sleeve being detachable.

2. A terminal clip comprising a body provided with terminal-attaching means, engaging means for an electric conductor, and an insulating member between said body and said conductor-engaging means, the parts being arranged to form a spark-gap between said engaging means and body.

3. The combination, in a terminal clip, of a body provided with terminal-attaching means, engaging means for an electric conductor, an insulating member between said body and said conductor-engaging means, the parts being arranged to form a spark-gap between said engaging means and body, and a sleeve mounted on said body and over the jointed members and adapted to be moved to expose said spark-gap.

4. A terminal clip comprising a body provided at one end with terminal-attaching means, an insulation plug inserted in said body at the other end, and a holding cap for an electric conductor mounted on the part of said plug that protrudes from said body and supported thereon out of contact with the body, one of the members mounted on the plug having a jump-spark projection that nearly bridges the space between said members.

5. A terminal clip comprising a body, terminal-gripping jaws pivotally attached to one end of said body, means to connect an electric conductor with the other end of said body, and a spring arranged and adapted to maintain said jaws normally in a closed

- condition, said jaws having their front ends so shaped that they can be forced apart against the resiliency of said spring when presented to a terminal.
- 5 6. The combination, in a terminal clip, with a hollow body, and a pair of terminal-gripping jaws pivotally attached to said body, such jaws having divergent rear edges, of a closure for the inner end of said body, and a spring in said body between said closure and said rear edges of the jaws, such spring being capable of operating said jaws to close them.
- 10 7. The combination, in a terminal clip, with a centrally bored and slotted body, and
- 15 a pair of terminal-gripping jaws pivotally attached in the slot to said body and each having a heel portion that extends behind its pivot, the edges of such heel portions being relatively divergent, of a closure for 20 the inner end of said body; and a spring and follower within the bore between said closure and said heel portions of the jaws, such spring being capable of operating said jaws to close them.
